(57) **CLAIM**

The ornamental design for an insulating sleeve for a beverage container, as shown and described.

DESCRIPTION

FIG. 1 is a perspective view of an insulating sleeve for a beverage container showing our new design;
FIG. 2 is a front elevation view thereof;
FIG. 3 is a back elevation view thereof;
FIG. 4 is a right side elevation view thereof.
FIG. 5 is a left side elevation view thereof.
FIG. 6 is a top plan view thereof;
FIG. 7 is a bottom plan view thereof;
FIG. 8 is a perspective view of a second embodiment of the insulating sleeve for a beverage container showing our new design;
FIG. 9 is a front elevation view of the second embodiment;
FIG. 10 is a back elevation view of the second embodiment;
FIG. 11 is a right side elevation view of the second embodiment.
FIG. 12 is a left side elevation view of the second embodiment.
FIG. 13 is a top plan view of the second embodiment; and,
FIG. 14 is a bottom plan view of the second embodiment. The broken lines in the figures are directed to environment forming no part of the claimed design or show portions of the insulating sleeve for a beverage container that form no part of the claimed design.
The shade lines in the figures show contour and do not claim surface ornamentation or treatment.
